UNITED STATES PATENT OFFICE.

AARON KEEPORTS, OF LANCASTER, PENNSYLVANIA.

CAR-COUPING.

SPECIFICATION forming part of Letters Patent No. 376,309, dated January 10, 1888.

Application filed May 3, 1887. Serial No. 236,909. (No model.)

To all whom it may concern:

Be it known that I, AARON KEEPORTS, a citizen of the United States, residing at Lancaster, in the county of Lancaster and State of Pennsylvania, have invented certain Improvements 5 in Car-Couplers, of which the following is a specification.

My invention relates to automatically acting car-couplers; and it consists in the construction 10 and combination of the various parts, as hereinafter fully described and claimed, and as illustrated in the accompanying drawings, which form part of this specification, in which—

Figure 1 is a plan or top view of one of my 15 couplers with portions of the casing of the draw-head cut away; Fig. 2, a side elevation of the same, also with portions of the casing cut away; Fig. 3, a longitudinal vertical section through the coupler; Fig. 4, a horizontal 20 section through the line $x-x$; Fig. 5, a front view of the coupler, and Fig. 6 a section of the bumper-face.

Similar letters refer to similar parts throughout the several views.

25 The main portion of the mechanism constituting my coupler is located inside of the casing A of the draw-head. This mechanism is divided into two distinct parts, that whereby the coupling-link B is automatically engaged 30 with the coupling-pin C and that by which the link is made to accommodate itself to the variations in the height of the cars which it is to connect. The coupling-pin is inserted in openings in the draw-head, as is ordinarily done; but in inserting it, it passes through a 35 cross-piece, d, connecting two vertical pieces or plates, D, passing through the draw-head casing inside of and adjoining the sides thereof. These plates D are strengthened below by a 40 cross-brace, d', similar to that above. The plates D have vertical slots d' cut therein, which are engaged with friction-rollers d³, pivoted in the back of the bull-nose N, inside of the plates.

45 Back of the bull-nose there is a cross bar, F, resting upon the lower plate of the casing, to the ends of which are attached two side bars, E. These side bars extend toward the vertical plates D, near which each is connected with 50 two lever-arms, e e'. The other ends of the lever-arms e are pivoted to the vertical bars D above the slots d', those of the arms e' to the spindle of the rollers d³. These lever-arms are so connected with the side bars, E, the vertical

bars D, and the spindles of the rollers d³ that 55 when the cross-bar F is moved forward, as will be hereinafter explained, the vertical bars D will be raised, so as to lift the coupling-pin from its socket c in the bottom of the draw-head high enough to permit the passage of any 60 coupling link B to be engaged with it.

The bull-nose has vertical slots n cut therein opposite to the lines of movement of the side bars, E, which permit the passage of the outer ends, e', of those arms through the bull-nose. 65 When the side bars, E, are moved forward, so as to raise the coupling-pin, these ends e' project beyond the face of the bull-nose, and when a car moving toward it with link in place for 70 coupling with the car with which it is connected strikes the ends of the bars E with its bull-nose it forces them back, so that the levers e e' are thrown back of the center and permit the fall and connection of the coupling-pin with the coupling-link. 75

The outer ends of the side bars are provided with upright cross-pieces e², extending above and below the ends of the side bars, and when the said side bars are thrust back into the draw-head they completely cover the slots n, to prevent the filling of the same with dirt or the entrance of projections from an opposite car. The cross-pieces e², when in the latter position just described, rest in a recess surrounding the slot n, so that their outer faces are flush 85 with the face of the bull-nose, thereby preventing their being crushed in any manner or any liability of causing buckling of the side bars, E. Another very important function performed by these cross-pieces is that they become engaged with the bull-noses of greater or less height than the projecting ends of the side bars, compensating for the differences in 90 the height of the cars to be coupled.

The side bars, E, are moved forward, so as 95 to project their ends beyond the face of the bull-nose, by means of a lever, G, having its fulcrum g in a slot, a, in the bottom plate of the casing. The inner end, g', of this lever is enlarged and rounded, so as to form a bearing 100 for the chain g², connecting the cross-piece F and the lever. Lateral motion of the cross-piece F and side bars, E, is prevented by means of a pin, f, projecting downward through a slot, a', in the bottom plate of the 105 casing.

It will be observed that whether the side arms, E, are moved back or forward the ends

of the lever-arms $e e'$ connecting with them are thrown somewhat beyond their center, so that a slight force applied when they are in one position readily changes them to the other.

5 The lower end, g^2 , of the lever G projects downward below the casing, and by it the bars E are moved forward to place said bars in the position for coupling automatically.

10 The inner face of the bull-nose back of the coupling-pin is concave in form and receives a link-bearing shell, M, of such convex form of the front face as to fit in the back of the bull-nose.

15 The shell M has an opening in front to correspond with that in the bull-nose, though somewhat larger, and is entirely open behind. It is rigidly secured above and below to the ends of the rods T and R, respectively, passing through openings in the casing of the draw-head. The rod T extends some distance above the draw-head and terminates in a handle, t, and has a spiral spring, t', coiled about it, one end secured against a circular lug, t², on the rod T and the other against the top plate of the casing. The rod R extends below the bottom plate of the casing, and is also surrounded by a spiral spring, r, one end bearing against the plate and the other against the annular flange r'. The upper and lower plates of the shell M are of much less thickness than the corresponding parts of the bull-nose, allowing considerable play. The outer corners of the coupling-links to be used with this bearing-shell are squared, as shown at b.

20 35 The end of the coupling-link, after passing and being engaged by the coupling-pin, rests in the bearing-shell M, and any turning of the handle t turns said shell and causes the outer end of the link to move to one side or the other to meet the bull-nose of a car with which it is to connect, and which may be somewhat out of the direct horizontal line for engaging. Force exerted upon the said handle t to raise or depress it also raises or lowers the end of 45 the link to enable it to engage a bull-nose of different height from that in which it rests.

Back of the shell M there are stops Q, to prevent the coupling-link being accidentally thrust too far back to engage with an adjoining car when coupling.

Having thus described my invention, what I claim as new, and desire to secure by Letters Patent, is—

1. In a car-coupler, the combination, with 55 the draw-head and coupling-pin, of the side bars, E, passing through the bull-nose and connected with the vertical bars D by levers $e e'$, the cross-piece d, for engaging the head of the coupling-pin, and the lever G, chain g^2 , 60 and cross-piece F, connecting the inner ends of the side bars, substantially as and for the purpose specified.

2. In a car-coupler, the combination, with 65 the draw-head and coupling-pin, of side bars connected with a lever, whereby they may be projected beyond the face of the bull-nose through slots in the face thereof, and arms

connecting said bars, and a frame for raising the coupling-pin, substantially as and for the purpose specified.

3. The combination, in a car-coupler, with 70 the draw-head and coupling-pin, of longitudinally-movable side bars, the bull-nose having slots therein through which said bars pass, and arms connecting said bars, and the frame 75 for holding the coupling-pin up when the draw-head is to receive a link, all constructed and operating substantially as specified.

4. The combination, in a car-coupler, with 80 the draw-head, of longitudinally-movable side bars passing through slots in the bull-nose, upright cross-pieces attached to the outer ends thereof, and mechanism for moving said bars forward through the slots, substantially as 85 and for the purpose specified.

5. The combination, in a car-coupler, with 90 the draw-head, of longitudinally-movable side bars passing through slots in the bull-nose, upright cross-pieces attached to the outer ends thereof, recesses about said slots in the outer face of the bull-nose, and mechanism for moving said bars forward through the slots, substantially as and for the purpose specified.

6. The combination, in a car-coupler, with 95 the bull-nose having a concave inner face, of a link-bearing movable shell with a convex front adapted to fit in the concave face of said bull-nose, rods rigidly attached to the top and bottom of said shell and projecting through openings in the upper and lower 100 plates of the casing, and springs coiled about said rods, substantially as and for the purpose specified.

7. The combination, in a car-coupler, with 105 the bull-nose having a concave inner face, of a link-bearing movable shell with a convex front adapted to fit in the concave face of said bull-nose, and a rod rigidly attached to the top of said shell and projecting through the upper plate of the casing, whereby the said 110 shell may be oscillated horizontally in the bull-nose, substantially as and for the purpose specified.

8. The combination, in a car-coupler, with 115 the bull-nose, of a link-bearing movable shell located back of said bull-nose and suspended between the upper and lower plates of the casing by a rod attached to the top of said shell, the rod passing through the upper plate of the casing, and a spring attached to the rod 120 and casing, whereby the elevation of the front of said shell may be varied, substantially as and for the purpose specified.

9. The combination, in a car-coupler, with 125 the draw-head, of a link-bearing shell located back of the bull-nose and having an opening extending through it from front to rear, and stops secured to the bottom plate of the casing back of said shell, substantially as and for the purpose specified.
